EPPA H. RYON, OF WORCESTER, MASSACHUSETTS, ASSIGNOR TO CROMPTON & KNOWLES
LOOM WORKS, A CORPORATION OF MASSACHUSETTS.

FILLING-THREAD-CUTTING MECHANISM.

939,445.

Specification of Letters Patent.

Patented Nov. 9, 1909.

Application filed April 17, 1907. Serial No. 368,781.

To all whom it may concern:

Be it known that I, EPPA H. RYON, a citizen of the United States, residing at Worcester, in the county of Worcester and State 5 of Massachusetts, have invented certain new and useful Improvements in Filling-Thread-Cutting Mechanism, of which the following is a specification.

My invention relates to a filling thread 10 cutting mechanism for the filling thread of a spent bobbin to be exchanged for a new bobbin in looms in which a magazine is used to hold the bobbins or filling carriers, and transferring mechanism is used to transfer a 15 bobbin from the magazine into the active shuttle, to take the place of the substantially exhausted bobbin in the shuttle.

The filling thread cutting mechanism in the class of looms referred to, is ordinarily 20 connected with some part of a transferring mechanism of the magazine, and is brought into operation through the operation of some part of the transferring mechanism, and in my present improvements my filling thread 25 cutting mechanism is also connected with some part of the transferring mechanism, and is brought into operation through the operation of some part of said mechanism.

I have only shown in the drawing a detached portion of a loom of the class referred to, with my filling thread cutting mechanism applied thereto, sufficient to enable those skilled in the art to understand the construction and operation thereof.

Referring to the drawing: Figure 1 is a 35 plan view of a detached portion of a loom at the magazine end, in this instance the right hand end, and of my improvements applied thereto. The magazine is not shown. Fig. 40 2 is a section, on line 2, 2, Fig. 1, looking in the direction of arrow a, same figure. Fig. 3 shows the parts shown at the right in Fig. 2 with the cutter in a different position.

In the accompanying drawing, 1 is a portion 45 of a loom side or end frame, 2 is the breast beam, and 3 a plate mounted on the upper side of the breast beam at the end thereof, and having a stand 4, shown in section, attached thereto, as a support for the 50 magazine, not shown.

5 is the lay beam, 6 a part of a stationary shuttle box on the end thereof, 7 is a part of a shuttle, and 8 a part of a bobbin in said shuttle.

55 9 is a dagger, carried on the lay beam and

extending out from the front side thereof, to engage the bunter, not shown, forming a part of the transerrer mechanism, and operate the transerrer mechanism, not shown, when said bunter is moved into the 60 path of the dagger by the filling detecting or indicating mechanism, in the usual way.

10 is the hand rail on the lay, and 11 the reed.

The temple 12 may be of the usual construction, and adjustably fastened to the temple rail or bar 13, secured to a stand 14 mounted on the breast beam 2.

15 is a portion of the woven fabric, and 16 is a filling thread leading from the selvage 70 or edge of said fabric to the shuttle 7.

All of the above mentioned parts may be of the usual and well known construction.

I will now describe my improvements in filling thread cutting mechanism.

The breast beam 2 has mounted thereon, in this instance an angle or corner plate 17, see Fig. 2, the downwardly extending part 17' of which carries a stud 18, on which is loosely mounted the hub 19' of an upright 80 lever 19. The upper arm of the lever 19 has a stud 19'' thereon, to which is pivotally connected one end of a connector 20. The other end of the connector 20 is connected to some part of the transferring mechanism, 85 not shown. The operation of the transferring mechanism on the operation of the filling detecting mechanism moves, through the connector 20, the filling thread cutting mechanism into two positions, one its inoperative position, shown in Fig. 2, and the other its operative position, shown in Fig. 3.

A spring actuated pin 21, mounted in lugs 17'' on the plate 17, forms a lock to yieldingly hold the lever 19 in its two positions, 95 the inner beveled end of said pin 21 entering a recess in the outer side of said lever 19.

When the lever 19 is moved into its operative position, it will extend into the path of a longitudinally moving rod 22, which in 100 this instance is loosely mounted to have a reciprocating movement in bearings 23' on a stand 23 secured upon the underside of the lay beam 5.

A helically coiled expansion spring 24 in 105 this instance encircles the rod 22, and bears at one end against a collar 27 fast on said rod, and at its other end against a bearing 23' on the stand 23. The spring 24 acts to move the rod 22 forward or toward the 110

breast beam 2, as shown in Fig. 2. The rear end of the rod 22 is in this instance pivotally connected with the lower end of a lever 25, which in this instance has its hub 25' pivotally mounted on a stud 26 on a stand 27 secured to the rear side of the lay beam 5, near the end thereof, see Fig. 1. The upper end of the lever 25 is in this instance made recessed or forked shaped, to receive the cutting blade 28, which is secured in position in this instance by rivets 29. The cutting blade 28 preferably extends between two dents of the reed 11, near the end thereof, see Fig. 1. The temple 12 has in this instance fast thereon at its outer end, a plate 30, preferably made of steel and having a grooved or recessed end, see Fig. 1, forming a pair of jaws to receive the cutting blade 28, as shown in Fig. 3, and cut the filling thread 16, which extends between the jaws 31 and the cutting blade 28, as the lay beats up.

The advantages of my improvements in filling thread cutting mechanism will be readily appreciated by those skilled in the art. They are of simple construction and operation, and may be readily applied to weft replenishing looms having a magazine of any ordinary and well known construction. The cutting mechanism is brought into operation on the indication of a change of filling, through the operation of the transferring mechanism.

It will be understood that the details of construction of my improvements may be varied if desired.

Having thus described my invention, what I claim as new and desire to secure by Letters Patent is:

1. In a filling thread cutter for looms, a cutter blade on the lay and a pair of jaws, on a stationary part of the loom, means for holding said cutter blade and said jaws out of engagement with each other during the normal operation of the loom, and means including connections to the filling transferring mechanism to cause them to be moved into engagement with each other on the forward beat of the lay, when a change of filling takes place, to sever the thread of the spent bobbin, and also the thread of the transferred bobbin.

2. In a filling thread cutter for looms, a pair of jaws located in front of the reed, a cutter blade adjustably mounted on the lay back of the reed, and means for moving said cutter blade and said jaws out of engagement with each other, during the normal

operation of the loom, and means including connections to the filling transferring mechanism to move said cutter blade between said jaws on the forward beat of the lay for two consecutive picks, when a change of filling takes place.

3. In a filling thread cutter for looms, a cutter blade situated on the lay and back of the reed line, and a pair of jaws, and means to hold said cutter blade out of engagement with said jaws during the normal operation of the loom, and means including connections to the filling transferring mechanism to cause said blade to enter said jaws on the forward beat of the lay for two consecutive picks when a change of filling takes place.

4. In a filling thread cutter for looms, the combination with the lay, and a movable cutter-blade carried thereon and adapted to extend through the reed, of jaws on a stationary part of the loom, adapted to receive said cutter-blade, the breast beam, and a pivoted lever thereon, said lever adapted to be moved into the path of a rod connected with the cutter-blade, to cause the movement of the cutter-blade on the forward movement of the lay.

5. In a filling thread cutter for looms, the combination with the lay, and a movable cutter-blade carried thereon, and adapted to extend through the reed, and jaws mounted upon a stationary part of the loom, and adapted to receive said cutter-blade, of the breast-beam, a pivoted lever thereon, said lever adapted to be moved into the path of a rod connected with the cutter-blade, to cause the movement of the cutter-blade, and a locking device for yieldingly holding said lever.

6. In a filling thread cutting mechanism for automatic filling replenishing looms, two sets of cutting surfaces, one situated on and movable with the lay, and the other situated on a stationary part of the loom, said cutting surfaces normally separated and out of contact with each other, and mechanism, including connections to the filling transferring mechanism, to cause said cutting surfaces to coöperate with each other, to sever the ends of the filling on the spent bobbin, and on the fresh bobbin, at each replenishment of filling.

EPPA H. RYON.
